UNITED STATES PATENT OFFICE

AMBROSE E. GREENE, OF BERKELEY, CALIFORNIA

QUICK-ACTING VISE

Application filed February 3, 1928. Serial No. 251,488.

My invention relates in general to vises or similar clamping devices and has particular reference to a so-called quick-acting vise of that general type described in my co-pending application, Serial No. 691,097, filed February 7, 1924.

One of the important objects of the present invention is to provide a vise in which certain essential parts of the construction or assembly thereof are so shaped that their surfaces may be machined or otherwise prepared by methods less costly than those which ordinary forms of vise construction make necessary.

Another object of my present invention is to provide a vise in which certain corresponding parts thereof, heretofore made integral, are made as separate parts and are so constructed that they can be strongly assembled, or easily removed, one from the other, for the purpose of replacement, resurfacing, or otherwise making changes in their contours or construction, as is frequently required or desirable.

Still another important object of my invention is concerned with the well-known fact that commercial cold-rolled steel is well adapted, in bar form, to serve as an accurate guide for sliding parts of the mechanism, and that when used for this purpose, it is lower in cost and stronger for any given analysis than cast or molded parts that have been machined to equal surface smoothness and to within limits of equal accuracy. I have therefore provided means of utilizing commercial cold-rolled steel to accurately position several of the vise parts, to re-inforce other of the parts and to guide the sliding jaw part of the vise. I thus accomplish economy of construction and increased strength as compared to other vises of a similar nature.

Still another object of my invention relates to means for increasing the facility with which a screw provided with undercut threads may be engaged or disengaged from an open-sided nut provided with similar threads.

In my application above identified, a screw and a nut of this character are described and are shown in the present application as incorporated in this general type of vise, ex-

cept that I now disclose the above referred to means for aiding the engagement and disengagement of the threads of the two parts. This improvement is applicable to many other forms of vises and claims that embody screws and nuts and I therefore have in mind the use of this construction in vises or other devices other than herein illustrated.

Other objects of the invention will appear hereinafter, the novel features and combinations being set forth in the appended claims.

In the accompanying drawing:—

Fig. 1 is a view in vertical section of a vise embodying the salient features of the present invention;

Fig. 2 is a view in cross section on the line 2—2 of Fig. 1; and

Fig. 3 is a detail view in end elevation of the fixed jaw part of the device.

Referring now to the drawings in detail: 10 represents the base of a vise having parallel top and bottom surfaces and provided with bolt slots 11 for securing the vise to a machine or work table. A guide plate or bar 12 surmounts and is adequately supported by the elevated longitudinally extending area 10' of the base 10. A fixed jaw 13 is provided with a channel in its lower surface which is adapted to snugly fit the plate 12. A sliding jaw 14 embraces the edges of the plate 12 as well as the elevated longitudinally extending area 10' of the base 10 and is thus mounted with freedom of sliding movement on these parts. The sliding movement of the movable jaw is readily and conveniently effected unless the same is held in fixed relation thereto. A socket 15 is provided in the sliding jaw 14 for the reception of the end of the actuating screw 16 and with a ball or knob 16' formed on the end of the actuating screw 16 to thus connect the screw to the jaw for universal movement. The ball or knob end of the screw is confined within the socket 15 by the machine screw 17 which is tapped into the socket 15 behind the ball or knob and without interfering with the free pivotal movement of the ball or knob within the socket.

The socket 15 is preferably constructed with parallel vertical sides, with outwardly

curved top and bottom walls, and preferably with a concave closed end substantially corresponding to the curvature or contour of the ball or knob 16'. In cross section, the vertical dimension of the socket is made considerably larger than the diameter of the ball or knob and its width between the parallel side walls is made only very slightly greater than the diameter of the ball or knob. The concave end wall of the socket is so shaped that, when the screw 16 is forced in the direction of the socket, the ball or knob on the end thereof will slide into center with the deepest point in the concave surface and this point is positioned so that when the knob or ball end of the screw is concentric with it, the periphery of the knob or ball 16' will be in contact with the bottom wall of the socket. A recess, aperture, or the like, opening 18 is provided in the bottom wall of the socket 15 for accommodating a compressed coil spring 19 which projects into the socket against the reduced diameter 18' of the screw between the termination of the threads and the ball or knob 16'. The purpose and function of this spring will be hereinafter more particularly referred to.

The manipulating handle 20 of the screw 16 is hingedly attached to the free end of the screw by means of a rivet, or the like, 21 which also serves as a pintle for a pivoted connection.

The open-sided nut 26 is provided with undercut threads adapted to fit the threads on the screw 16 for holding the sliding jaw in predetermined fixed relation to the fixed jaw 13 or else for effecting a gradual and fine adjustment with the jaw by rotating the screw by the handle 20 while the threads thereof are engaging the threads of the nut. In other words, for making a quick adjustment of the sliding jaw 14, the screw 16 is lifted out of engagement with the nut 26 which releases it for quick sliding movement whereas by lowering the screw so that the threads thereof engage the threads of the nut 26, rotation of the screw may be effected by the handle 20 for tightly clamping an object between the fixed and sliding jaws and holding the sliding jaw in such clamping position. This function and operation of the screw is all clearly described in my co-pending application above identified.

The nut 26 is mounted upon the plate 12 by the bolt 27 and the bolt also serves to mount the plate upon the base 10.

The cap screw 28 extends upwardly through an opening in the base 10 made to receive it, through an opening in the plate 12 made to receive it, and is tapped into the fixed jaw 13 to clamp these parts of the device securely in place in a manner similar to the use of the bolt 27. Both the bolt 27 and the cap screw 28 are preferably fitted snugly in the openings through which they project with the

exception of the openings in the base 10 which are preferably made larger in diameter, respectively, than the bolt and cap screw in order to obtain the assurance that stresses incidental to clamping pressures between the jaws of the vise will be sustained by the steel plate 12 and will not, in as great a measure, act through the base 10, which may therefore be of weaker and less expensive material. In Fig. 1, the part 29 illustrates an object clamped between the jaws 13 and 14 of the device.

It is preferable that the top and bottom surfaces of the base 10 be machined substantially parallel and that the machining operations for this purpose can be readily accomplished by disc grinding; whereas, if the base and fixed jaws were cast integral, as in ordinary vise construction, the operation of surfacing the upper side of the base could not be done on a disc grinder but would require planing or milling. The same also applies to the working face of the fixed jaw. It is well-known by those familiar with machine-shop and manufacturing methods that the operation of disc grinding is one of great economy, as compared with the milling or planing of flat metal surfaces; and it is evident that inasmuch as the parts embodied in the present invention have, by novel shapes and arrangements, been made susceptible of being machined by this means, new and useful improvements and economies have been accomplished by me in the art.

By making the base and fixed jaw as described, it is possible to place between them a plate having opposite surfaces smooth and parallel and which will serve as a guide for the sliding jaw; and, further, that cold-rolled steel is well adapted without modification for this purpose; and that, means being provided permitting this use, several expensive machining operations, which would otherwise be required, become unnecessary.

A further feature of advantage in this invention is made evident by observing the fact that by a unique arrangement and shaping of parts it has been made possible to retain the base, guide plate, fixed jaw, sliding jaw, and nut all in strongly assembled relation, by means of one bolt and one cap screw, which represents a degree of simplicity and economy not before evidenced in vise construction.

I do not wish to be limited to only two fastening elements, such as the bolt 27 and the cap screw 28, because it would be equally within the scope of the invention to use a plurality of such elements; but I do not wish to emphasize the fact that it is advantageous, for reasons hereinbefore explained, to make a vise in which the fixed jaw, guide plate, nut and base are separable elements; and that, by means of the constructional principles specified, the number of said fastening elements necessary to insure rigidity and trueness of

the assembly of these several parts has been reduced to a minimum as compared with other vises.

The operation of the vise and the functioning of the spring 19 will now be described. By using the handle 20 the screw 16 is lifted out of engagement with the nut 26, and the sliding jaw is freely and quickly moved to just admit placing in the vise the object to be held. The screw 16 is then engaged with the nut 26 and is rotated to clamp the said object between the jaws. This clamping effect results from the travel of the screw in the nut, which travel forces the ball end of the said screw into the socket 15 in the jaw 14. This movement, as previously explained, causes the said ball end of the screw to slide into center with the deepest point in the concave end of the socket 15. The coil spring 20 19 is compressed by this action, and the several parts are so proportioned that when this position is reached, the axis of the screw 16 is concentric with the axis about which the threads in the nut 26 were generated, thereby bringing about the full and uniform engagement between the thread of the screw 16 and the thread of the nut 26.

The object held in the vise is released by reversing the operation just described, and it will be observed that in this reverse process the spring 19 acts to lift the ball end of the screw 16 in the socket 15. This action takes place as soon as reverse rotation of the screw 16 relieves the pressure with which it was forced into said socket. The effect of thus raising the ball end of the screw 16 is to partly disengage the interlocking undercut surfaces of the threads of the screw 16 and nut 26. I have found that when this has taken place, the handle end of the screw can easily and freely be lifted, completely disengaging the screw from the nut; whereas, otherwise, when the nut 26 is relatively long, and as the jaw 16 approaches a position far removed from the jaw 13, the interlocking threads tend to stick in engagement with each other, causing inconvenience.

It should be understood, however, that while the spring 19 is desirable for the reasons specified, it is not essential and may be omitted, if desired, the screw 17 being relied on to confine the semi-spherical head or knob 16' in the socket 15 adjacent the bottom thereof in the jaw 14. When the spring 19 is omitted and the vise is operated in the manner illustrated in Fig. 1, the head 16' will center itself by sliding up to the position shown in the dotted lines in Fig. 1. In other words, when clamping pressure is exerted by operation of the device, the head 16' will be pressed against the bottom of the socket 15 where the concave surface is so positioned that it will cause the knob 16' to move to a location where the axis of the screw 16 is concentric with the axis of the screw-

threads on the half-nut so as to assure the full and uniform engagement between the threads of the screw 16 and the threads of the nut 26. The screw 17 may be of sufficient length to prevent the head 16' from being withdrawn from the socket 15 without interfering with the centering action of the head 16' and without interfering with the free release of the screw 16 from the half-nut 26 whenever desired.

A further advantage incidental to this described action of the spring 19 is that the handle end of the screw 16 need not be lifted as entirely clear of the nut 26 when it is desired to slide the jaw 14 quickly to any position.

Obviously those skilled in the art may make various changes in the construction and arrangement of parts without departing from the spirit and scope of the invention as defined by the claims hereto appended, and therefore I do not wish to be restricted to the precise construction herein contained.

Having thus fully described and shown an embodiment of my invention, what I claim and desire to secure by Letters Patent of the United States, is:—

1. In a vise, the combination with a base having a bottom recess, a guide plate mounted thereon, a fixed jaw, a bolt operable in said recess for securing rigidly together said base and said plate and said fixed jaw, a movable jaw guided along said plate, means for operating said movable jaw comprising an open-sided nut mounted on said plate, and means for bolting said open-sided nut to said plate and said base, said bolting means being operable from the recess in the bottom of said base.

2. In a quick-acting vise, the combination with a base, of a guide plate surmounting said base, a sliding jaw carried by said guide plate, a fixed jaw secured to said guide plate, an open-sided nut secured to said guide plate, an operating screw having one end extending into a socket in said sliding jaw, means for preventing said screw from becoming detached from said socket while the latter permits flexibility of movement of said screw for engagement with and disengagement from said open-sided nut, said operating screw and said open-sided nut having undercut threads, a spring in said socket in position to press upwardly the end of said operating screw in said socket to assist in releasing the operating screw from said open-sided nut when said operating screw is released, and a conical depression in said socket to afford a cam to move said operating screw into position where its axis will be concentric with the axis of the threads of the open-sided nut when the operating screw engages said nut and the movable jaw presses the work against the fixed jaw.

3. In a vise, the combination with a base

member of a jaw secured to said base member, a jaw slidably mounted on said base member towards and away from said fixed jaw, a screw having operative engagement with one of said jaws at a point substantially along the longitudinal axis of said screw, and a half nut secured to the other of said jaws and adapted to co-operate with said screw, interlocking threads on said screw and nut to prevent relative movement of said screw away from said nut without the aid of any auxiliary pressure means acting transversely to the axis of said screw and towards said nut.

4. A vise comprising a pair of jaw members relatively movable on a base member, one of said jaws being secured to said base member, a screw having engagement with one of said jaws adjacent one end of said feed screw, an open sided nut operatively connected to the other of said jaws and adapted to occupy a fixed position relatively thereto, means for applying clamping pressure to said screw to move said jaws towards each other, means for alining the axes of said screw and nut, means for moving said screw so as to move the axis thereof out of alinement with the axis of said nut, and interlocking threads on said nut and screw adapted to hold said nut in engagement with said screw while clamping pressure is being applied to said screw and without the aid of auxiliary pressure producing means acting transversely to the axis of said screw and towards said nut.

5. A vise comprising a pair of relatively movable jaw members mounted on a base, a screw having a loose connection with one of said jaws, a half nut rigidly connected to the other of said jaws, alining means for alining the axis of said screw with the axis of said nut when clamping pressure is applied to said screw, and a spring for cooperating with the jaw engaging end of said screw for moving the screw to a position such that the axis of said screw is out of alinement with the axis of said nut when the clamping pressure is removed, said nut and screw having undercut threads which prevent the removal of said screw from said nut while clamping pressure is being applied thereto, said screw being adapted to be moved out of engagement with said nut by manual means after said spring has moved said jaw engaging end in the manner set forth.

6. A vise comprising a pair of relatively movable jaw members mounted on a base, a screw having a loose connection with one of said jaws, a half nut rigidly connected to the other of said jaws, alining means for alining the axis of said screw with the axis of said nut when clamping pressure is applied to said screw, and a spring for cooperating with the jaw engaging end of said screw for moving the screw to a position such

that the axis of said screw is out of alinement with the axis of said nut when the clamping pressure is removed, said nut and screw having undercut threads which prevent the removal of said screw from said nut while clamping pressure is being applied thereto, said screw being adapted to be moved out of engagement with said nut by manual means after said spring has moved said jaw engaging end in the manner set forth, said alining means comprising a spherical head on said screw adapted to engage a curved surface of a recess forming a part of the loose connection between said screw and its respective jaw, the other part of said loose connection being the said spherical head which is received within said recess.

7. A vise comprising a base, a jaw movably mounted on said base, a half nut on said base, a screw co-operating with said nut and having one end thereof loosely received within a recess in said jaw, undercut threads on said screw and nut, and a spring for raising the jaw engaging end of said screw so that when manual means is applied to the other end of said screw to lift said screw out of engagement with said nut, there will be no binding between the co-operating undercut threads on said screw and nut to thereby prevent removal of said screw from said nut.

8. In a vise the combination with a sliding jaw having a recess adapted to pivotally retain one end of a feed screw, a feed screw having one end thereof fitted within said recess, a half nut co-operating with said screw, said nut and screw having co-operating undercut threads, means within said recess whereby, when clamping pressure is applied to said screw to move said nut the end of said screw in said recess is guided to a position therein, such that the axes of said screw and nut are substantially in alinement, and a yielding means to press against said screw whereby, when said clamping pressure is released, the end of said screw engaged in said recess will be moved to another position wherein the recess of said screw is out of alinement with the axis of said nut without disengaging said screw from said nut.

9. A vise comprising a screw, an open sided nut, undercut threads on said screw co-operating with similar threads on said nut, an abutment arranged to be moved by means of pressure exerted by said screw, means for directing said pressure to be applied against a certain portion of said abutment, and other means for changing the position of said screw with respect to said abutment when said screw is not exerting pressure on said abutment, and without disengaging said screw from said nut, to thereby facilitate disengagement of said nut and screw when manual

means is applied to said screw for this purpose.

10. A vise comprising a fixed jaw and a movable jaw, an open sided nut, a screw pivotally connected to said movable jaw and adapted to co-operate with said nut, interlocking threads on said screw and nut, means for depressing the pivoted end of said screw when pressure is exerted against the end thereof, and spring tension means adapted to elevate the pivoted end of said screw when said pressure is relieved and without disengaging said screw from said nut and for the purpose of assisting manual disengagement 15 of said screw and nut.

In testimony whereof I have signed my name to this specification on this 27th day of January, A. D. 1928.
